UNITED STATES PATENT OFFICE.

CHARLIE WESTERLUND, OF BIRMINGHAM, ALABAMA, ASSIGNOR OF ONE-THIRD TO
F. W. BOSTROM, OF CHICAGO, ILLINOIS.

HEATER ATTACHMENT FOR GRATES AND STOVES.

1,383,506.

Specification of Letters Patent.

Patented July 5, 1921.

Application filed June 10, 1919. Serial No. 303,230.

To all whom it may concern:

Be it known that I, CHARLIE WESTERLUND, a citizen of the United States of America, residing at Birmingham, in the county of 5 Jefferson and State of Alabama, have invented certain new and useful Improvements in Heater Attachments for Grates and Stoves, of which the following is a specification.

10 My invention relates to a hot air heating attachment for grates, stoves and furnaces and has for its object to take advantage of the waste heat, that is now lost with the 15 escaping products of combustion, to produce a volume of hot air which will assist materially in heating the room in which the grate or stove is placed or which can be adapted to heat other rooms or compartments.

20 My invention contemplates the provision of an air heater disposed above the fire and arranged in conjunction with baffles so as to cause the products of combustion to have a long and circuitous course in close contact 25 with the walls of the air heating chambers, and my invention further contemplates the arrangement of such chambers so as to form shallow baffles provided with partitions which direct the air in a circuitous course 30 therethrough.

My invention further contemplates the provision of means to draw the cold air from near the floor and deliver it into the air heating chambers which in turn deliver 35 the heated air to an overhead hot air radiator, designed so as to produce a pleasing and ornamental appearance to the fire place and to have the least possible interference with the normal operation or appearance of 40 the fire place.

My invention is more particularly adapted for use in fire places and has been illustrated in this embodiment in the accompanying drawing, in which:—

45 Figure 1 is a front view of the fire place equipped with my improved air heating attachment with the folding blower in operating position.

Fig. 2 is a vertical sectional view taken on 50 the line 2—2 of Fig. 1.

Fig. 3 is a top plan view of the apparatus.

Fig. 4 is a sectional view taken on the line 4—4 of Fig. 2.

Similar reference numerals refer to similar parts throughout the drawings.

As illustrated, a fire place or grate opening 1 has a grate 2 of any ordinary construction suitably mounted therein. Preferably the back wall of the fire place is left straight so as to provide as much space as possible for the air heating attachments so that they can be set into the wall in such manner that they will project but little into the room. In the upper part of the fire place I mount a hot air heater comprising 60 a lower horizontal heating chamber 4, a vertical section 5 connecting the lower chamber with a similar horizontal upper heating chamber 6. This connecting portion 5 is disposed against the back wall 3 of the fire 65 place opening and is tied thereto by retaining lugs or lips 7 or in any other suitable manner. The heating chambers 4 and 6 of the heater are spaced apart and they extend from side to side of the fire place opening, thus forming a pair of spaced baffles 70 connected only at the rear by the section 5 and having their adjacent spaced walls disposed in parallelism. Each upper and lower chamber of the hot air heater is divided 75 along its center from front to rear by a solid vertical partition wall 8 and each subdivided chamber thus produced is provided with transverse staggered baffles 9 so arranged as to produce a circuitous course for 80 the air traversing the chamber from front to rear or vice versa.

On each side of the fire place I provide a cold air pipe 10 which is shown circular and provided with air inlet slots 11 in its base 85 which rests on the floor. These pipes extend above the top of the air heater and there support a rectangular hot air receiving chamber or register 12 having air discharge holes 13 in its front face. This register is narrow 90 in width and extends entirely across above the fire place. It will set in close against the chimney wall and thus be comparatively inconspicuous. If desired, it may be designed to have an ornamental appearance. 95 Each pipe 10 is provided with a solid transverse partition 14 just above the level of the lower chamber 4 of the air heater and each pipe, below this partition, is provided with a lateral outlet pipe 15 which connects with 100 the inlet port 16 at the front side edges of the heater chamber 4. The cold air thus enters this lower heater chamber in opposite directions from each front corner and flows inwardly toward the division wall 8. 105 110

The air is divided by the partition 8 and baffles 9 so that it flows in a circuitous course rearwardly as indicated by the arrows in Fig. 3, until it enters the rear section 5 near 5 its center and is there deflected by a horizontal partition 5^a which stops short of the sides of the section so as to provide ports 17 through which the partially heated air passes upwardly through the section 5 into 10 the rear corners of the upper heater chamber 6, through which it flows in a circuitous course forwardly, controlled by the partition 8 and baffles 9 until it reaches the front corners of this upper heater chamber which 15 are provided with side ports 18 through which the hot air passes to short pipe connections 19 and flows therethrough back into the pipes 10 above the partitions 14. The hot air rises through the tops of the pipes 10 and 20 enters the radiator 12 at its opposite ends and flows therethrough, being distributed into the room through the openings 13.

To obtain the maximum heating efficiency from the products of combustion I provide a 25 metal heater front 20 having a vertical wall connected along its bottom edge to a bottom horizontal wall 21 which projects inwardly to a point above the outer edge of the grate 2. Along its upper edge the front 20 is connected to a top horizontal wall 22 which passes under the bottom edge of the radiator 12 and under the top edge of the fire place opening back to the chimney flue 23. The front 20 is spaced substantially from 30 the forward edges of the heater and it is provided with a middle baffle horizontal plate 24 which extends midway between the heater chambers 4 and 6 and parallel therewith to a point near the heater section 5. This partition extends from side to side of 35 the fire place. Preferably the front sections 20, 21, 22 and 24 are so designed as to form with the air heating chambers a circuitous passage of substantially uniform cross sectional area for the products of combustion, 40 this passage opening below the heater near the front of the fire place and opening above the heater near the rear of the fire place into the chimney flue. The bottom edge of the 45 front section 21 is down turned at 25 and is connected by hinges 26 to a folding blower plate comprising the hinged sections 27 and 28, the latter of which is provided with a handle 29 and adapted to hang below the top 50 of the grate. When the sections of the blower are folded up one on the other and swung upwardly and outwardly they are adapted to be caught and held by a spring catch 30 attached to the center of the front, 55 which thus serves to hold the blower when folded so that it will be hardly noticeable.

In the passage for the products of combustion formed between the heater chamber 6 and the front section 22 I provide a damper 60 65 31 pivotally mounted on the heater and pro-

vided with a handle or control rod 32 projecting through the front so that the damper may be adjusted to the desired position to control the draft.

In operation, the fire is started in the grate 70 in the customary manner after which the blower is dropped to operating position shown in Figs. 1 and 2. This causes a quick starting of the fire and brings the heating apparatus rapidly to heated condition. The 75 products of combustion flow through the circuitous passage provided therefor, first passing under and then over the heater chamber 4, then under and over the heater chamber 6, and then to the flue. The cold air is drawn 80 in from near the floor through the ports 11 in the pipes 10 and delivered into the heater and in making its long passage therethrough the air becomes highly heated and is finally discharged into the room through the register 12. The hot air will pass through the heater in a volume proportionate to the heat to which the air heater is exposed, as the hot air therein will tend to rise and pass 85 into the register and the rapidity of its flow will be proportionate to the heat radiated to it. The arrangement of the front and air heating chambers is such as to provide the maximum radiating surface exposed to the products of combustion and the heater itself 90 is designed to give a maximum length of travel of the hot air in its flow therethrough. The blower is folded up to dotted position, Fig. 2, after the fire is well started, whereupon the fire in the grate will give out its 95 radiation heat with a pleasant and comfortable effect to the occupants of the room. The consumption of the fuel can be controlled by the regulation of the damper 100 so as to obtain the maximum heating efficiency therefrom.

The cold air pipes and the air register together will form a pleasant and ornamental appearance surrounding the fire place. The air heater is especially designed so that it can 105 be easily manufactured and installed and the parts of the heater and register can all be inexpensively manufactured from sheet metal.

This invention is not intended to be restricted in scope to the specific embodiments shown, but contemplates such modifications as come within the spirit and scope of the claims.

Having thus described my invention, what 120 I claim as new and desire to secure by Letters Patent, is:—

1. An air heating grate attachment for fire place opening comprising a relatively thin air conducting casing adapted to conform to the horizontal cross section of the fire place opening and to be mounted as a baffle in the top portion of the fire place opening only, a front member disposed across and in front of the top of the fire 125 130

place opening and adapted to direct the products of combustion about the outer edge of the heater casing, air conduits connected to the heater casing at its front corners and disposed to set in front of the chimney, and a top radiator disposed above and in front of the chimney and having communication with said casing, substantially as described.

2. The combination with a fire place, a
10 grate and a flue for the products of combustion, of an air heater mounted in the top only of the fire place and disposed in the path of the products of combustion, said heater comprising spaced air heating chambers forming baffles, baffle means to direct the products of combustion in a circuitous course under and over the spaced air heating chambers, and baffle means to cause the air to flow circuitously through said chambers.
15
20

3. The combination with a fire place, a grate and a flue for the products of combustion, of an air heater mounted in the top only of the fire place and disposed in the 25 path of the products of combustion, said heater comprising communicating spaced air heating chambers forming baffles, baffle means to direct the products of combustion in a circuitous course under, between and 30 over the spaced air heating chambers, and baffle means to cause the air to flow circuitously through said chambers.

4. An air heating attachment for fire places comprising an air heater composed of upper and lower horizontal transverse hollow chambers connected at the rear only and disconnected at the front, and a front spaced from the said chambers and having connected thereto a horizontal baffle disposed substantially midway between the upper and lower air chambers and forming therewith a circuitous passage adapted below to receive the products of combustion from the fire place and above to discharge them into the chimney flue.

5. An air heating attachment for fire places comprising an air heater forming a baffle across the top of the fire place and composed of upper and lower horizontal transverse chambers communicating at the rear only and there arranged to engage the rear fire place wall, and a front wall depending in front of said chambers and having connected thereto a horizontal baffle disposed substantially midway between said chambers to form a circuitous passage adapted below to receive the products of combustion and above to discharge them into the chimney flue, in combination with a draft regulating damper interposed in said passage for the products of combustion.

6. An air heating attachment for fire places comprising vertical air ducts adapted to rest on the floor and having cold air inlets

at their bottom, a baffled air heating casing 65 substantially horizontally disposed and having its front portion mounted on and communicating with said air ducts, the main body portion of said air heating casing being adapted to project into and to itself 70 form a baffle across the upper portion of a fire place opening, said casing having walls forming a circuitous passage for the products of combustion through said casing, and an air register above said casing and having 75 communication therewith to receive heated air therefrom.

7. An air heating attachment for fire places comprising vertical air ducts adapted to rest on the floor and having cold air inlets 80 at their bottom, a baffled air heating casing substantially horizontally disposed and having its front portion mounted on and communicating with said air ducts, the main body portion of said air heating casing being adapted to project into and to itself form a baffle across the upper portion of a fire place opening, said casing having walls forming a circuitous passage for the products of combustion through said casing, and 85 an air register mounted on the upper ends of said air pipes above said casing and having communication therewith to receive heated air therefrom. 90

8. The combination with a fire place, a 95
grate and its chimney, of double baffle air
heating chambers disposed in the path of the
products of combustion in their passage to
the flue and having its front portion project-
ing to the front beyond the fire place, 100
an overhead register mounted on the over-
hung front portion of and having connec-
tion with the hot air heating baffle and side
air supply pipes which support said over-
hung front end of the air heating baffle 105
chambers, and communicating therewith,
substantially as described.

9. An air heating attachment for fire places comprising a pair of upright air pipes having air inlets at their bottom ends and which are adapted to stand in front of and to each side of the fire place opening, a baffled air heating chamber having its front end communicating with and supported by said pipes, said casing being adapted to form a horizontal baffle across the upper portion of a fire place opening with a circuitous passage therethrough for the products of combustion, an air register mounted on and communicating with the upper ends of said pipes, connections from the air heater to the upper ends of said pipes, and a partition in the pipes between the upper and lower connections therefrom to the air heating casing. 110 115 120

10. In combination, a hot air heater comprising transverse parallel shallow body portions having hot air chambers therein which communicate at the rear; and a heater front

spaced from the forward ends of said air heater sections and comprising a bottom extension, which projects partly under and is spaced from the under portion of the heater, 5 and an intermediate baffle plate which is spaced midway between the air heater sections and terminates adjacent to their rear

portions, and means to mount said heater in the upper part of an ordinary fire place, substantially as described.

In testimony whereof I affix my signature.

CHARLIE WESTERLUND.
